THOMAS H. KENVIN, OF HOMESTEAD, PENNSYLVANIA.

INGOT-MOLD STOOL.

1,157,697.

Specification of Letters Patent. Patented Oct. 26, 1915.

Application filed March 5, 1915. Serial No. 12,380.

To all whom it may concern:

Be it known that I, THOMAS H. KENVIN, a citizen of the United States of America, residing at Homestead, in the county of Allegheny and State of Pennsylvania, have invented certain new and useful Improvements in Ingot-Mold Stools, of which the following is a specification.

The present invention relates to improvements in ingot mold stools in the class of metal founding.

In the process of casting steel ingots it is customary to pour the molten metal into the molds, and in so doing the weight of the molten metal and the heat from the metal frequently make holes in or pits the stool or plate to such an extent that a plate cannot stand many castings before it is worn out. The continued use of the mold and continued action of the molten metal on the stool or bottom of the mold finally wears away the stool, thus causing the stool to be discarded and a new one is required to replace it. I have devised a removable and replaceable plug for the stool which will eliminate the scrapping of useful material which will perform the functions of the part required, and which may be discarded when worn or broken and replaced by a new and fresh piece, thus prolonging the life of the stool as a whole. Thus the stool will last indefinitely and all that is scrapped in the new device is the removable center piece of the stool when it becomes worn or broken.

In the accompanying drawings I have illustrated one complete example of the physical embodiment of my invention constructed according to the best mode I have so far devised for the practical application of the principles of my invention.

In the drawings: Figure 1 is a side elevation of a duplex mold for ingots and its carriage, embodying the features of my invention. Fig. 2 is a top plan view of the device of Fig. 1, one of the molds however being omitted for convenience of illustration. Fig. 3 is a partial side elevation and partial sectional view. Fig. 4 is a transverse sectional view on line 1—1 of Fig. 2. Fig. 5 is a bottom plan view of the "stool" which forms a part of my invention. Fig. 6 is a side elevation of the removable center plug or replaceable bottom for the mold, to be seated in the stool.

In illustrating the preferred embodiment

of my invention I have employed the usual carriage or car body 1 supported upon the wheels 2 to travel upon the tracks 3 as customary, and the duplex molds 4 and 5 are the standard ingot molds open at top and bottom, and formed with side lugs 6 for lifting purposes.

The two molds are supported upon the "stool" 7 which is a metallic plate designed to rest upon the flat floor of the car body, and form the base or support for the two molds 4 and 5.

The body of the stool is steel and is formed with integral upwardly projecting side and end flanges 8 to encompass the bottom end of the molds 4 and 5 and retain them in position on the stool.

As best shown in Fig. 5, there are two holes or openings 9 and 10 extending through the stool with flaring walls *i. e.* the opening is greater in area at the top of the stool plate than at its bottom. In Fig. 3 it will be clearly seen that the body of the car is also provided with openings as 11, and these openings which are located in position to register with the openings 9 and 10 are of the same size or area as the lower end of the openings in the stool. It will also be noted in this figure that the interior area of the open bottom of the mold 5 is less than the maximum area of the opening 9 in the stool. These two sets of registered openings 9—11 and 10—11 are designed to receive the cast iron plug 12 which forms the bottom to the ingot mold. In Fig. 6 the construction of the plug is apparent, and it will be understood that the upper flaring portion 13 is adapted to seat in the flared or beveled-face opening of the stool, while the lower portion 14 projects through the opening in the stool and into the opening 11 in the car body. Thus this plug not only serves as a bottom for the mold, but performs the additional function of locking the stool on the car body to prevent possible shifting of parts.

The plug 12 is locked to the stool by means of a latch bar 15 which is freely passed through the center loop 16 on the plug and bears upwardly against the under face of the two oppositely disposed bosses 17 formed integral with the stool and projecting downwardly therefrom, at the edge of the openings 9 and 10 in the stool. In Figs. 4 and 5 this construction is clearly shown and will be readily understood, and it will be appar-

ent that the plug can be removed from the stool, only after the stool has been removed from the car body. This latch prevents upward accidental displacement of the mold 5 bottom or plug, and of course the beveled walls in engagement with the beveled faces of openings 9 and 10, and the squared portion 14 of the plug in the openings 11, all prevent lateral displacement of the plug or 10 bottom member.

In use the parts are assembled by first locking the plugs in the stool openings, then locating the stool on the car body with the squared portions 14 fitted in the squared 15 openings 11, and finally placing the molds 4 and 5 in situ between their retaining flanges and upright on the stool as in Fig. 1. The mold is now ready for pouring and this is accomplished in usual manner. It will 20 be noted that the weight of the molten metal is transferred from the center plug or bottom member to the steel stool and car body, because of the beveled sides of the plug and side walls of the stool openings, and the 25 proportionate dimensions of the lower open end of the molds and the greater maximum area of the plug insures proper conditions for forming the ingot in the mold.

From the above description taken in connection with the drawings it is apparent 30 that I have provided a facile, economical and efficient means for overcoming objections and difficulties inherent in a solid or one piece stool, as now customarily used, 35 and eliminated extra and unnecessary expense accompanying the old method of manufacturing stools.

Particular attention is called to the saving 40 in manufacturing cost of stools by the use of the steel body to the stool and the replaceable center piece or plug, and the cost of maintenance is also reduced by the fact that instead of scrapping the whole stool, it is necessary to scrap only the center-piece or 45 plug when it becomes worn. Instead of making the whole stool of a single integral piece, it will be noted that the stool is composed of a single steel body with interchangeable and removable cast iron centers 50 or plugs, and in some instances these plugs may be made of steel if desired.

What I claim is:—

1. The combination in a mold with a supporting member having an opening therein, of a stool formed with a corresponding 55 opening having flaring sides, and a plug formed with beveled sides in the flaring opening and a locking portion in the opening in the supporting member.

2. The combination in a mold with a supporting perforated member, of a stool formed with a corresponding but flaring opening, a plug fitted in the flaring opening and having a portion projecting in the perforated member, and an open bottom 65 mold with an interior cross area of less dimensions than the maximum or top area of the plug.

3. The combination with a carriage having an opening, a stool thereon having a 70 corresponding but flaring opening, a mold and retaining flanges on the stool for the mold, and a plug forming the bottom of the mold fitted in the flaring opening and having a member projecting in the carriage 75 opening to lock the carriage and stool together.

4. The combination with a stool having an opening therein with upwardly flaring sides, of a plug formed with beveled sides 80 and seated in said opening, and locking means carried by said plug for locking the plug in the stool.

5. The combination with a stool having an opening with flaring walls, of a plug 85 with beveled sides fitted therein and formed with a bottom loop, a latch bar passed through said loop, and retaining bosses on said stool at the edge of the opening for said latch bar. 90

6. The combination with a perforated supporting member, a stool having a corresponding but flared opening and retaining bosses, of a plug fitted in the flared opening and having a latch bar therein engaging said 95 bosses, substantially as described.

In testimony whereof I affix my signature in presence of two witnesses.

THOMAS H. KENVIN.
